UNITED STATES PATENT OFFICE.

JOHN W. SARGENT, OF PROVIDENCE, RHODE ISLAND.

ENGINE-GOVERNOR.

986,762.

Specification of Letters Patent. Patented Mar. 14, 1911.

Application filed September 6, 1910. Serial No. 580,700.

To all whom it may concern:

Be it known that I, JOHN W. SARGENT, of the city and county of Providence and State of Rhode Island, have invented certain new and useful Improvements in Engine-Governors; and I do hereby declare the following specification, taken in connection with the accompanying drawings, forming a part of the same, to be a full, clear, and exact 10 description thereof.

My invention relates to engine governors of that class ordinarily known as "shaft-governors" and has for its objects to eliminate excessive strain and friction on the 15 journals or pivots in governors of this class due to the centrifugal force of the weight and tension of the spring, and to provide a governor having great power and facility of adjustment.

20 To these ends the invention consists in the novel construction and combination of parts hereinafter described and claimed.

In describing my invention in detail reference will be made to the accompanying 25 drawings, in which—

Figure 1 is a side elevation of the fly-wheel of an engine showing my novel form of governor attached thereto. Fig. 2 is an 30 end view partly in section. Fig. 3 is an enlarged side view of the governor showing the same at its latest cut-off position. Fig. 4 is a similar view showing the governor at its earliest cut-off position.

Referring to the drawings, 1 represents 35 the engine-shaft and 2 the fly-wheel mounted thereon. An eccentric 3 is mounted to swing on a pivot 3' secured in the hub 2' of the fly-wheel 2. Extending laterally from the eccentric 3 is a bent arm 4 which has its 40 free end pivotally connected at 5 to one end of a link 6. The other end of the link 6 is pivotally connected at 7 to one end of a rocker-arm 8. The rocker-arm 8 is pivoted near its center at 9 to the fly-wheel 2, and a 45 centrifugal weight 10 is pivoted at or near its center of gravity at 11 to the opposite end of said rocker-arm 8.

As shown in Fig. 1, the center line of effort or combined strain of the springs is 50 radial from the center of shaft 1, and the arc of motion of the pivot 11 is approximately in this same radial line.

A series of springs 12, 13, 14, and 15, of 55 equal size and tension, are each pivotally connected at one end to the centrifugal weight 10 on the side adjacent the shaft 1

and are each pivotally connected at the opposite end to the rim of the fly-wheel, said springs being arranged substantially at right angles to the weight 10, and the 60 springs 12 and 13 being located upon one side of the shaft 1 and the springs 14 and 15 being located upon the opposite side of said shaft.

With the above construction it will be 65 seen that, as the centrifugal weight 10 moves in or out from said shaft 1, the weight and springs maintain their same rectangular relation and there is practically no turning action of the springs upon their pivots and that none of the centrifugal or 70 spring strain comes on the pivot 11.

It is obvious that any spring connection 75 may be made with the weight 10, whereby the spring effort is substantially in a radial line from the center of the engine-shaft through pivot 11 of the weight.

The arrangement of this governor has the advantage of the governor-weight being in 80 gravity balance with the eccentric and strap.

What I claim as my invention and desire 85 to secure by Letters Patent is:

1. In a device of the character described, the combination, with an eccentric, of an actuating rocker-arm, a centrifugal weight 90 pivoted on said rocker-arm and adapted to move said rocker-arm in one direction, and a spring attached to said weight and adapted to move said rocker-arm in the opposite direction.

2. In a device of the character described, the combination, with an engine-shaft, of an eccentric, an actuating rocker-arm, and a spring actuated centrifugal weight, pivoted on said rocker-arm, the arc of motion of 95 said weight pivot and center line of spring effort being both approximately in a radius from the center of said engine-shaft.

3. In a device of the character described, the combination, with an eccentric, of an actuating rocker-arm, a centrifugal weight pivoted near its center of gravity on said rocker-arm, and a series of springs attached to said weight and arranged and adapted to resist the centrifugal force of said weight. 100

4. In a device of the character described, the combination, with an eccentric, of an actuating rocker-arm pivoted near its center, means connecting one end of said rocker-arm to said eccentric, a centrifugal weight pivoted near its center of gravity on the other end of said rocker-arm, and a spring 105 110

attached to said weight upon each side of its pivot and arranged and adapted to resist the centrifugal force of said weight.

5. In a device of the character described, the combination, with an engine fly-wheel, of an eccentric and an actuating rocker-arm pivotally mounted thereon, a centrifugal weight pivotally mounted on said rocker-arm, and a series of springs connected at one 10 end to said weight and at the other end to the rim of said fly-wheel, said springs extending upon opposite sides of the axis of said fly-wheel and at right angles to said centrifugal weight.
- 15 6. In a device of the character described, the combination, with an engine fly-wheel, of an eccentric pivotally mounted thereon, a

lateral arm secured to said eccentric and pivotally connected to a link, a rocker-arm pivoted near its center to the fly-wheel and at 20 one end to said link, a centrifugal weight pivoted near the other end of said rocker-arm and having its center of gravity substantially at its pivot, a series of springs pivotally connected at one end to said weight 25 and at the other end to said fly-wheel, the arc of motion of the weight pivot and the center line of spring effort being both approximately in a radius from the axis of said fly-wheel.

JOHN W. SARGENT.
